COMBINED TABLE AND IRONING BOARD

Fred Dahl, Clear Lake, S. Dak.

Application August 6, 1936, Serial No. 94,687

3 Claims. (Cl. 38—105)

This invention relates to the class of furniture and pertains particularly to a novel combination of table and ironing board structure.

The primary object of the present invention is to provide a table having an ironing board built thereinto and having a shiftable top portion whereby when the said top portion is shifted to one position the ironing board may be withdrawn into working position in the plane of the table top.

Another object of the invention is to provide a combined table and ironing board in which the table is provided with a slideable leaf portion which, when moved in one position, uncovers a housing in which an ironing board is located, the ironing board being removable to a position in the same plane as the table top and the shiftable leaf portion thereof.

A still further object of the invention is to provide a structure of the above described character wherein the said shiftable leaf and the ironing board are spring controlled so that upon the release of a holding means for the leaf the latter will automatically move laterally in the plane of the table top and the ironing board will be automatically projected out to its working position in the plane of the table top.

The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in the appended claims.

In the drawing:

Figure 1 is a view in perspective of a combined table and ironing board embodying the present invention;

Figure 2 is a sectional view through the table on a plane passing across one edge of the board and leaf and showing the latter extended;

Figure 3 is a sectional view similar to Figure 2 showing the ironing board housed in the casing with the leaf covering the opening;

Figure 4 is a section taken on the line 4—4 of Figure 3.

Referring now more particularly to the drawing, wherein like numerals of reference designate corresponding parts throughout the several views, the numeral 1 generally designates a table, the top of which is indicated by the numeral 2.

Forming a part of the top is a leaf 3 which has a tongue 4 along each longitudinal edge and these tongues engage in corresponding grooves 5 in the abutting edge portions of the adjacent top pieces. It will thus be apparent that the leaf 3 may be shifted longitudinally to form an opening through the table top.

Formed beneath the top of the table and beneath the opening in which the leaf 3 moves is a box or housing 6 which extends the full width 10 of the table and which is closed at its bottom and four sides, the only access to this housing being through the top of the table when the leaf 3 is shifted.

Secured to the under side of the leaf 3 is one 15 end of a coil spring 7 which has its other end attached to the side apron portion 8 of the table structure. This spring is, of course, disposed within the housing 6 and it is normally under tension so that when the leaf 3 is released by 20 the holding means about to be described it will function to slide the leaf laterally. This lateral sliding movement of the leaf is limited by a transversely extending cleat 9 which is secured to the under side of the leaf and which limits the 25 movement of the leaf by being brought into abutting relation with the apron portion 8 to which the spring 7 is attached.

As illustrated the leaf 3 is set into the top 30 of the table adjacent one edge thereof so that there is only a relatively narrow portion of the top at one side of the leaf. This narrow top portion is indicated by the numeral 10 and at a suitable point is provided with the transverse bore 11 which is formed in the outer edge and extends 35 inwardly toward the opening in which the leaf 3 positions. In this bore is a shiftable latch pin 12 and the leaf 3 is provided with an edge recess 13 which is drawn into alignment with the bore 11 when the leaf is in a position to completely fill the table top opening. This pin 12 retains the leaf against movement under the movement of the spring 7.

Adapted to be housed in the casing 6 is an ironing board 14 which is of a width to substantially fill the opening in the table top when the leaf 3 is shifted laterally. This board 14 has its forward end or nose supported in any suitable manner, as by the bracket 15 which is inclined downwardly into the housing 6, so that when the leaf 3 is moved laterally or outwardly to uncover the board closing housing, the board may be shifted outwardly in a direction opposite that in which the leaf is moved by the spring 7. The board 14 adjacent its rear end has secured to 50 55

its underside the transverse cleat 16 and also secured to the under side of the board adjacent this end is a coil spring 17 which has its opposite end secured to that depending portion of 5 the table structure which forms a continuation of the skirt 8 and which extends across or closes the end of the housing 6 opposite the end to which the spring 7 is connected.

The board 14 also has formed in one side edge 10 and adjacent its rear end, the opening 18 which, when the board is moved outwardly to operative position under the influence of the spring 17, comes to position in alignment with the bore 11 so that the pin 12 can be reinserted for engagement 15 in the opening 18 and thus secure and support the inner end of the ironing board in working position. As will be apparent, the cleat 16 which is secured to the ironing board limits this movement outwardly as the cleat 9 of the 20 leaf limits the movement of this portion of the structure in a direction opposite to that in which the ironing board moves.

From the foregoing it will be apparent that when the ironing board is housed in the casing 25 6 and the leaf is held in place by the pin 12, the removal of the pin will permit the spring 7 to shift the leaf outwardly in one direction and when this occurs the leaf will no longer hold the forward end of the ironing board in place 30 and the spring 17 will then become effective to slide the ironing board out in the opposite direction until the cleat 16 stops its movement. The ironing board may then be raised to the plane 35 of the table top and secured in place by reinserting the pin 12 so that its inner end will engage in the opening 18 in the edge of the bore.

I claim:—

1. In a table structure of the character described, a top having an opening extending the 40 full width thereof, a leaf filling said opening, sliding connecting means between the edges of the opening and the edges of said leaf permitting the leaf to be shifted laterally to uncover the opening, a board having a width through a 45 portion of its length sufficient to fill a portion of the opening when the leaf has been shifted to one position therein, said leaf when shifted to said one position having an end projecting beyond one side of the table top and said board

when in the opening having an end projecting beyond the opposite side of the table top, supporting means beneath the table top for the board when the leaf is in position to entirely fill the opening, means for retaining the leaf in opening filled position, and resilient means connected with the leaf and the board whereby upon release of said retaining means the leaf and board will move in opposite directions to dispose them in projecting relation with the sides of the table top as described. 10

2. In a structure of the character described, a table having a top provided with an opening extending the full width thereof, a leaf filling said opening, a sliding connection between the edges of the leaf and the edges of the opening, a casing disposed beneath said opening, latching means for securing said leaf in opening filling position, a spring connecting the under side of the leaf with a fixed part of the body of the 15 table at a point to effect the shifting of the leaf laterally when the latching means is released to partially uncover the opening, a board having a width through a portion of its length sufficient to fill the opening, said board being of a size to 20 be housed in said casing when the leaf is in opening filling position, spring means coupling the under side of the board with a fixed part of the table and so arranged as to project the board from the casing when the opening is uncovered, 25 and said latching means engaging and securing the board in projected position, said spring means for the leaf and board operating to project the same in opposite directions. 30

3. In a table of the character described, a top 35 having an opening therein, a leaf filling said opening and movable in one direction in the plane of the top to partly uncover the opening, a board having a width to fill the uncovered portion of the opening, means beneath the top for supporting the board beneath the leaf when the latter is in closing position in the opening, means for projecting the board into the opening opposite to the direction of movement of the leaf when the leaf is moved to open position, and means 40 for retaining the board in the opening in the plane of the top. 45
